CLAIM

The ornamental design for a personal computer, as shown and described.

DESCRIPTION

FIG. 1 is a reduced perspective view of a personal computer shown in a horizontal position showing my new design;

FIG. 2 is a reduced perspective view thereof shown in a vertical standing position;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.
The display and keyboard shown in broken lines in FIGS. 1 and 2 are shown for illustrative purposes only and form no part of the claimed design.

FIG. 1

FIG. 3

FIG. 5

FIG. 4

FIG. 6

FIG. 7

FIG. 8
